UNITED STATES PATENT OFFICE.

FRANK A. SEIBERLING, OF AKRON, OHIO, AND ALEXANDER STRAUS, OF NEW YORK, N. Y.; SAID STRAUS ASSIGNOR TO THE GOODYEAR TIRE AND RUBBER COMPANY, OF AKRON, OHIO.

VULCANIZING-PRESS.

SPECIFICATION forming part of Letters Patent No. 658,471, dated September 25, 1900.

Application filed December 9, 1898. Serial No. 698,745. (No model.)

To all whom it may concern:

Be it known that we, FRANK A. SEIBERLING, residing at Akron, in the county of Summit and State of Ohio, and ALEXANDER STRAUS, residing at New York, in the county of New York and State of New York, citizens of the United States, have invented a certain new and useful Improvement in Vulcanizing-Presses, of which the following is a specification.

Our invention has relation to improvements in presses for vulcanizing pneumatic tires; and the objects of our invention are to produce a new and improved press of the class 15 designated that shall be simple in construction and easily operated, will permit of interchangeable molds for different sizes of tires with different external marks or configurations, and in which the interior of the tire 20 will be charged during the process of vulcanization with live steam under pressure, and finally to hasten the process of vulcanization.

To the aforesaid objects our invention consists in the peculiar and novel construction, 25 arrangement, and combination of parts hereinafter described, and specifically pointed out in the claims, reference being had to the accompanying drawings, forming a part of this 30 specification.

In the drawings, in which similar reference-numerals indicate like parts in the different views, Figure 1 is a side elevation of our improved vulcanizing-press; Fig. 2, a plan of 35 the same; Fig. 3, a section, enlarged, at the line $x-x$ of Fig. 1, showing the upper face of the lower mold and annular case with the steam-tube for inflating the tire; Fig. 4, a section, enlarged, at the line $y-y$ of Fig. 2; Fig. 40 5, an enlarged view of the free end of the steam-inspirating tube, and Fig. 6 an enlarged horizontal section of the flexible joint of the steam-tube.

Referring to the drawings, 1 is an annular 45 hollow metallic case supported on legs 2. Extending from one side of this case are arms 3, having semicircular notches 4 to form bearings for the opposite case of the press, and lugs 5, projecting from its inner periphery 50 and provided with bolt-holes for attaching

the lower mold. Above this case is a similar annular hollow case 6, adapted to rest on and register with the case 1 and provided with similar lugs 7, having bolt-holes for attaching opposite molds and having hollow journals 8, adapted to rest in the bearings 4 and internally connected with the case 6, and a handle 28 for raising this case and mold. 55

The case 6 is provided with an arm 9 and counterweight 10, retained by a set-screw to 60 permit the upper case to be easily raised. The cases 1 and 6 are locked together by means of links 11, pivoted between lugs 12 on the lower case 1 and resting between similar lugs on the upper case 6 and drawn tight by 65 forked pivoted levers 13, having eccentric ends that bear on the upper face of the case 6. Each case 1 and 6 is heated by live steam from pipes 14, that enter the ends of journals 8 through swivel-joints and by branches 15 70 to the lower case 1. The opposite halves of the molds 16 and 17 are mounted in the cases 1 and 6 by means of bolts 18, passing through the respective lugs 5 and 7 of the corresponding halves of the molds. These molds are 75 arranged to accurately register by means of an annular tongue and groove, as shown in Fig. 4.

In the inner face of the case 1 is a pipe 19, internally connected with the case, to which 80 pipe, by means of a swivel-joint 20, a pipe 21 is connected, provided with a valve 22, a cock 23, and a non-conducting handle 24 and terminating in a pointed tube 25, having side vents near its pointed end, as shown in Fig. 5. 85 The valve 22 operates to open and close the pipe 21, and the cock 23 has an exhaust-pipe 26, through which the steam may escape back from the tire when the vulcanizing process is completed. The hollow spaces in the cases 1 90 and 6 do not extend entirely around them, but are interrupted by a barrier in each at the hinge side, as indicated in dotted lines in Fig. 2, the object of which is to secure more even distribution of steam about the cases. 95

In operation, the cases with the molds in place being open and charged with live steam, a prepared unvulcanized tire is placed in the mold, and in this operation the tube 25 is inserted in the valve-stem placed on the tire 100

for the valve afterward to be inserted, the joint 20 permitting the pipe 21 and tube to be rocked up for that purpose and brought down with the tire, and when down the tube rests 5 outside of the molds in a shelf 27 and in oppositely-disposed notches in the molds. The upper case 6 is then rocked down and locked to the lower case 1. The valve 22 is then opened and the cock 23 closed, permitting 10 live steam to enter the interior of the tire. In a short time, usually about three minutes, the tire, from the combined effect of external and internal heat, is completely vulcanized, when the valve 22 is closed and the cock 23 15 opened, the former shutting off the further entrance of live steam and the latter permitting the steam in the tire to escape through the pipe 26. By hinging the cases together they are readily opened to permit the placing 20 and removal of tires and to change the molds when desired without danger of burning the operator or want of time. The counterweight 10 constantly overbalances the weight of the case 6, and hence by no accident can the two 25 cases strike together and crush the hands of the operator, as where in the case of those vulcanizers where the upper case rises vertically any breaking of the machinery, the constant tendency is to fall and may result in 30 catching the operator while at work.

We claim as our invention—

1. In a press for vulcanizing pneumatic tires the combination of a fixed annular hollow case, a movable annular hollow case 35 hinged at one side thereto, tire-forming molds detachably mounted in said cases and arranged to register, clamping devices for locking said cases together and means for intro-

ducing and controlling the entrance of live steam into said cases, substantially as shown 40 and described.

2. In a press for vulcanizing pneumatic tires, the combination of two annular hollow cases, hinged together at one side, tire-forming molds detachably connected with said 45 cases and arranged to meet and register, clamping devices for locking said cases together, means for introducing and controlling the entrance of live steam into said cases, and a tube having a flexible joint and arranged to carry live steam into the interior 50 of a tire in said molds, and means for controlling the entrance of steam in said tube, substantially as shown and described.

3. In a vulcanizer the combination with a 55 fixed annular hollow case and a free annular hollow case hinged to and adapted to register with the fixed case, of pipes to connect with a steam-supply connected with the interiors of said cases, devices for locking said cases 60 together, molds arranged to rest in said cases, a counterweight to balance the free end of the free case, a pipe flexibly connected with one of said cases having a hollow tube with a lateral opening arranged to rest in the tire 65 between said molds, and a valve and an exhaust-cock in said pipe, all constructed and arranged substantially as shown and described.

In testimony that we claim the above we 70 hereunto set our hands.

FRANK A. SEIBERLING.
ALEXANDER STRAUS.
